SHOPPING CART ATTACHMENT

Melvin Cohen, 150 Dayton Ave.,
Passaic, N.J. 07055

Filed Nov. 16, 1966, Ser. No. 4,699

Term of patent 14 years

(CL. D14—3)

FIG. 1

FIG. 2

FIG. 4

FIG. 3

FIG. 5

FIG. 1 is a front elevational view of a shopping cart attachment showing my new design;

FIG. 2 is a side elevational view thereof, the opposite side being identical;

FIG. 3 is a rear elevational view thereof;

FIG. 4 is a top plan view thereof; and,

FIG. 5 is a bottom plan view thereof.

I claim:

The ornamental design for a shopping cart attachment, as shown and described.
